COMBINED FILING AND STORAGE CABINET AND VIEWING SCREEN FOR PHOTOGRAPH TRANSPARENCIES

Robert W. Haggard, Hamilton, Ontario, Canada

Application August 29, 1955, Serial No. 37,688

Term of patent 14 years

(Cl. D61—1)

The figure is a perspective view of a combined filing and storage cabinet and viewing screen for photograph transparencies, showing my new design; the side and end of the cabinet which is not shown being plain.

I claim:

The ornamental design for a combined filing and storage cabinet and viewing screen for photograph transparencies, as shown and described.
